UNITED STATES PATENT OFFICE

2,569,763

SLIDABLE DOOR FOR CABINETS

George F. Hofferberth, Dayton, Ohio, assignor to
 General Motors Corporation, Dayton, Ohio, a
 corporation of Delaware

Application July 14, 1949, Serial No. 104,648

2 Claims. (Cl. 312—295)

1

This invention relates to refrigerators and particularly to a door arrangement therefor.

I am aware of the fact that refrigerator cabinets having an opening in the top wall thereof, affording access to a refrigerated chamber therein, have been provided with sliding doors having rollers thereon wherein an end of one door rolls on another door and has its other end supported by and rollable on a single track which supports the doors. Such a door arrangement eliminates the necessity of providing two tracks at different elevations for two doors. Heretofore in providing the doors with rollers, to substantially eliminate friction between the doors in moving them on their track or upon one another, the rollers would space the lower face of the upper door a slight distance above the upper face of the lower door thus necessitating the use of a gasket along either the upper face of the lower door or the lower face of the upper door in order to seal the space between the doors. The use of such a gasket creates friction between the doors, when they are moved relative to one another, by wiping across the surface of one of the doors and this friction retards the easy rollability of the doors on a track. I contemplate the elimination of such a gasket in a double rollable door arrangement while at the same time providing means whereby the doors seal against one another when in closed position to prevent relatively warm room air from entering the refrigerated chamber of the refrigerator cabinet.

An object of my invention is to provide an improved arrangement for sealing one door to another door of a double rollable door structure employed to close the access opening of a refrigerated chamber of a refrigerator cabinet.

Another object of my invention is to provide a double rollable door arrangement for opening and closing a chamber access opening in the top wall of a refrigerator cabinet in which arrangement one end of one door rolls on the top surface of the other door to open a portion of the access opening and when moved into closed position it moves in a vertical direction and engages an end of the other door to seal the access opening.

In carrying out the foregoing objects it is a further and more specific object of my invention to locate roller means on one door of the double door arrangement a predetermined distance from its end which overlaps an end of the other door upon which it is rolled so that the roller means moves past the end of the other door when both doors are shifted to closed position to permit the

2

one door to move downwardly into overlapping sealing engagement with the other door.

Further objects and advantages of the present invention will be apparent from the following description, reference being had to the accompanying drawing, wherein a preferred form is clearly shown.

In the drawing:

Fig. 1 is a perspective view of a low temperature refrigerator cabinet having my door arrangement embodied therein;

Fig. 2 is an enlarged fragmentary vertical sectional view taken on the line 2—2 of Fig. 1, showing both doors of the present double door arrangement in closed position;

Fig. 3 is a view similar to Fig. 2 showing one of the doors of the present door arrangement moved into a partially open position;

Fig. 4 is a fragmentary transverse sectional view taken on the line 4—4 of Fig. 3 showing an end view of the doors; and

Fig. 5 is an enlarged fragmentary sectional view taken on the line 5—5 of Fig. 3 showing the mounting of a roller on one of the doors.

Referring to the drawing, for illustrating my invention, I have shown in Fig. 1 thereof a refrigerator cabinet generally represented by the reference character 8 and having outer metal panels or walls 9. Cabinet 8 includes an open-top metal tank or liner 11 (see Fig. 2) surrounded by insulating material 12 within the walls 9 and forming an open-top food storage chamber 14 therein. The cabinet has an elongated opening in its top wall corresponding to the open top of liner 11 and providing access to the chamber 14. An insulated throat structure generally represented by the reference character 15 lines the opening in the cabinet top wall as is conventional in the art. A machine compartment located at one end of the cabinet 8 is closed by the louvered panels 16 and houses a refrigerant translating device of a closed refrigerating system including an evaporator in the form of a conduit coil 17 wrapped around and secured in intimate thermal contact with the outer surface of walls of liner 11. The refrigerant translating device may be of the type including a motor-compressor unit and a condenser (not shown) and well known to those skilled in the art. Operation of the motor-compressor unit of the refrigerant translating device, under control of a thermostat or other suitable device, causes absorption of heat from chamber 14 by refrigerant in the evaporator 17 to cool the interior of the chamber and causes the refrigerant to be evap-

orated and withdrawn from the evaporator. The evaporated refrigerant flows to the compressor where it is compressed and forwarded to the condenser wherein it is cooled and liquefied. Liquid refrigerant flows from the condenser into the evaporator 17 under the control of a suitable restrictor or expansion valve. A closed refrigerating system of the type described is well known to those skilled in the art and is shown in many patents. For this reason such showing has not been duplicated in the drawing of the present application.

My invention is particularly directed to a novel door arrangement for sealing the cabinet open top or the access opening leading to the food storage chamber 14. Since the interior of chamber 14 is maintained at a temperature well below freezing for the freezing of food products and storage of frozen foods it is desirable to insure that the access opening of chamber 14 is tightly closed except when access to the chamber is required. In the present disclosure a metal frame 21, having an outwardly directed flange 22 at its upper edge and an inwardly directed flange 23 at its lower edge, is forced into and tightly fitted in the opening bounded by the throat structure 15 in the cabinet top wall. The upper flange 22 extends entirely around the frame 21 and engages the cabinet top wall about the opening therein while the lower flange 23 forms a track 25 extending continuously in a single horizontal plane along the long sides of the elongated opening in the cabinet top wall. Flange 23 also extends around the end portions of the elongated frame 21 to increase the structural strength of the frame. A first door 27, of any suitable or desirable construction, has a roller 28 on each of its sides and adjacent the ends thereof. The rollers 28 project below the lower surface of door 27 and are rollable upon and along the track 25. A second door 31, also of any suitable or desirable construction, has its one end supported upon and rollable along track 25 by providing on each side thereof a depending bracket 32 to which a roller 33 is attached. The other end of door 31, opposite the rollers 33, overlaps and normally rests upon the end of door 27 when both doors 27 and 31 are closed (see Fig. 2). A roller 34 on each side of door 31 projects from the lower surface thereof and is spaced a predetermined distance from its overlapping end for a purpose to be presently described. As before stated the doors 27 and 31 may be of any suitable or desirable construction and preferably each door carries at its end, adapted to abut against the upright ends of frame 21, a soft rubber sealing gasket 36 for sealing the doors to the frame when they are moved to closed position as shown in Fig. 2. Each door 27 and 31 is provided with a knob or handle 37 and 38 respectively to facilitate movement of the doors along track 25 on the rollers. The doors 27 and 31 fit snugly against the upright longitudinal side portions of frame 21 and these side portions of the frame serve to guide the doors in their horizontal movement along the track 25. The rollers 28 and 34 are located in recesses provided in the underside of doors 27 and 31 (see Fig. 5) while rollers 33 are secured to the legs of the inverted substantially U-shaped brackets 32. Each roller 28, 33 and 34 is mounted upon a shaft or pin 41 (see Fig. 5) riveted or otherwise suitably secured to the door. As before stated the doors may be of any suitable or conventional construction and they may be of the type including a two-part bounding frame having

a plurality of spaced apart layers of plate glass clamped therebetween so as to render the interior of the refrigerated chamber 14 visible through the doors. The two parts 43 and 44 of the door bounding frames may be bolted together or secured to one another in any well known or suitable manner with a strip 45 of molded plastic material clamped therebetween (see Fig. 5) and extending along the one end, opposite the end thereof carrying the gasket 36, and the two sides of each door. It is well known that such molded plastic material readily slides on surfaces of other materials without creating any appreciable amount of friction and therefore the strips 45, particularly at the sides of the doors, extend a slight distance outwardly of the door frames so as to serve to prevent binding of the doors during movement thereof.

When it is desired to gain access to the chamber 14 either door 27 or 31 may be moved horizontally relative to the other to uncover or open a portion of the elongated access opening of chamber 14. For example, handle 37 may be grasped and door 27 moved to the right as viewed in Fig. 2 of the drawing. This movement of door 27 causes the upper rounded corner of the end of the door to strike the rollers 34 and further movement of door 27 causes the rollers 34 and door 31 to be lifted upwardly and permits the rollers 34 to roll along the upper surface of door 27 to thus open the lefthand side of the chamber access opening. When the rollers 34 ride over the end of door 27 the rollers 34 space the lower surface of door 31 from the upper face of door 27. Upon moving the door 27 to the left to close the access opening of chamber 14 the end of door 31, opposite the gasket end 36, moves past or to the left of the rollers 34 on door 31 and door 31 then drops downwardly into overlapping engagement with the end of door 27. When it is desired to gain access to the interior of chamber 14 at the righthand end thereof as viewed in Fig. 2 of the drawing, handle 38 is grasped and door 31 moved to the left. This movement of door 31 causes the rollers 34 to strike door 27 and ride over the upper rounded corner of the end of door 27 whereupon the lefthand end of door 31 is lifted upwardly, about the rollers 33, relative to door 27 and rollers 34 roll upon the top surface of door 27 to uncover the righthand side of the access opening of chamber 14 (see Fig. 3). When door 31 is moved to the right to close the chamber access opening, with the door 27 in closed position, the rollers 34 ride past the end of door 27 and permit the end of door 31 to drop downwardly into overlapping engagement with the end of door 27 (see Fig. 2).

In my novel double rollable door arrangement the position of the end of door 31 in overlapping engagement with the end of door 27 forms a seal to prevent heat leakage into chamber 14 at a point between the doors. My novel arrangement of sealing the doors to one another when both doors 27 and 31 are closed eliminates the necessity of providing a sealing gasket or the like on one of the doors in a position whereby the gasket would drag or scrape on the other door, when the doors are moved relative to one another. Another advantage obtained by dropping the upper door downwardly into sealing engagement with the lower door in my double door arrangement affords, to the operator of the doors, an indication that both doors are tightly

closed with the sealing gasket on the end thereof in abutting engagement with the end walls of the access opening. This relieves the user of the refrigerator cabinet of the task of frequently checking the doors to insure that they are tightly closed.

While the form of embodiment of the invention as herein disclosed, constitutes a preferred form, it is to be understood that other forms might be adopted, as may come within the scope of the 10 claims which follow.

What is claimed is as follows:

1. A refrigerator cabinet having a plurality of walls forming a chamber therein, the top wall of said cabinet having an opening therein providing access to said chamber, a first door and a second door cooperating therewith for opening and closing different portions of said chamber access opening, said second door having a part thereof normally overlapping and supported upon the top of an end portion of said first door, said second door being movable over a substantial portion of said first door in a horizontal direction for opening one portion of said chamber access opening, roller means carried by said second door and adapted, when said second door is moved over said first door, to roll thereon and vertically space said second door from said first door, and said roller means being spaced a sufficient distance from the end of said overlapping part of said second door to cause said second door to drop downwardly into sealing engagement with said top end portion of said first door when both doors are moved into their closed positions.

2. A refrigerator cabinet having a plurality of walls forming a chamber therein, the top wall of said cabinet having an opening therein providing access to said chamber, means forming a

track along two opposed sides of said chamber access opening, a first door and a second door associated with said track and cooperating with one another for opening and closing different portions of said chamber access opening, said second door having a part thereof normally overlapping and supported upon the top of an end portion of said first door, said second door being movable over a substantial portion of said first door in a horizontal direction for opening one portion of said chamber access opening, roller means adjacent each end of said first door and rollable along said track, roller means adjacent one end of said second door and rollable along said track, roller means carried by said second door adjacent said end portion of said first door and adapted, when said second door is moved over said first door, to roll thereon and vertically space said second door from said first door, and said last named roller means being spaced a sufficient distance from the end of said overlapping part of said second door to cause said second door to drop downwardly into sealing engagement with said top end portion of said first door when both doors are moved into their closed positions.
